CLAIM

The ornamental design for a toothbrush, as shown and described.

DESCRIPTION

The present application file contains at least one drawing executed in color. Copies of this patent or patent application publication with color drawing(s) will be provided by the Office upon request and payment of the necessary fee.

FIG. 1 is a perspective elevation view of a toothbrush;

FIG. 2 is a front plan view thereof;

FIG. 3 is a right side elevation view thereof;

FIG. 4 is a rear plan view thereof;

FIG. 5 is a left side elevation view thereof;

FIG. 6 is a top plan view thereof;

FIG. 7 is a bottom plan view thereof;

FIG. 8 is a perspective elevation view of a toothbrush;

FIG. 9 is a front plan view thereof;

FIG. 10 is a right elevation side view thereof;

FIG. 11 is a rear plan view thereof;

FIG. 12 is a left side elevation view thereof;

FIG. 13 is a top plan view thereof;

FIG. 14 is a bottom plan view thereof;

FIG. 15 is a perspective elevation view of a toothbrush;

FIG. 16 is a front plan view thereof;

FIG. 17 is a right side elevation view thereof;

FIG. 18 is a rear plan view thereof;

FIG. 19 is a left side elevation view thereof;

FIG. 20 is a top plan view thereof;

FIG. 21 is a bottom plan view thereof;

FIG. 22 is a perspective elevation view of a toothbrush;

FIG. 23 is a front plan view thereof;

FIG. 24 is a right side elevation view thereof;

FIG. 25 is a rear plan view thereof;

FIG. 26 is a left side elevation view thereof;

FIG. 27 is a top plan view thereof; and,

FIG. 28 is a bottom plan view thereof.

The stippling in FIGS. 1-7 represents a contrast in color.
